COMBINED SOLDERING IRON HOLDER AND TRANSFORMER UNIT

Carl E. Weller and Donald R. Fegley, Easton, Pa., and
Alden J. Brassaw, Phillipsburg, N.J., assignors to Weller
Electric Corporation, Easton, Pa., a corporation of
Pennsylvania

Filed Mar. 23, 1964, Ser. No. 79,121

Term of patent 14 years

(Cl. D26—1)

FIG-3

FIG-4

FIG-5

FIGURE 1 is a perspective view of a combined soldering iron holder and transformer unit embodying our new design;

FIGURE 2 is a side elevation view thereof, the opposite side being the same;

FIGURE 3 is a top plan view thereof;

FIGURE 4 is an end elevation view thereof as seen from the right of FIGURE 3; and

FIGURE 5 is an end elevation view thereof as seen from the left of FIGURE 3.

We claim:

The ornamental design for a combined soldering iron holder and transformer unit, substantially as shown and described.
